UNITED STATES PATENT OFFICE

2,437,359

SNUBBED TRUCK

Raymond C. Pierce, Chicago, Ill.

Application July 27, 1944, Serial No. 546,826

26 Claims. (Cl. 105—197)

1

My invention relates to a railway car truck and more particularly to a type of truck commonly called quick wheel change, wherein the side frame, and spring group and the supported bolster are so constructed and arranged as to permit the application or removal of the bolster from the bolster opening while the spring group remains in normal position on the spring seat in the side frame.

The general object of my invention is to provide a novel relatively simple and easily controlled snubbing arrangement for such a type of railway car truck wherein the snubbing elements may be wholly confined within the end of the bolster for engagement with friction faces afforded on the spaced columns of the side frame.

A more specific object of my invention is to provide an improved form of snubbed quick wheel change railway car truck wherein friction shoes are mounted at opposite sides of each bolster end and resilient means is compressed between the shoes and so arranged as to afford sufficient downward component against the friction shoes as to overcome any tendency of the shoes to slide upwardly away from their seat against the bottom portion of the bolster as the bolster moves downward. Such tendency, of course, will not be present as the bolster is moving upwardly.

It has been found that it is highly desirable to maintain the friction shoes at a constant position with respect to the bolster as far as vertical movements are concerned so that there will be no play between the shoe and the bolster during such vertical movements and a constant snubbing effect may thereby be secured by the friction shoes against the adjacent side frame columns. My novel arrangement comprehends such a device as that described wherein a relatively heavy spring or springs may be arcuately preformed and positioned between the friction shoes at opposite sides of the bolster end and wherein guide means is provided on the bolster end so that said spring will be maintained in such a position as to afford the required downward component against the shoes. In my novel arrangement each friction shoe has a diagonally arranged spring seat against which one end of the before-mentioned arcuate spring may seat in order to secure the before-mentioned vertical force component on the shoe and prevent lost motion between the shoe and the bolster.

My invention comprehends a novel arrangement such as that above referred to, wherein a plurality of friction shoes may be supported in

each end of the bolster and arranged for engagement with the respective side frame columns between which the bolster end may be confined and wherein a single arcuate coil spring or a plurality of arcuate coil springs may be compressed between the shoes at opposite sides of the bolster and arranged to bear against a wall of the bolster in such manner as to afford the desired vertical component already referred to.

In the drawings,

Figure 1 is a fragmentary side elevation of a railway car truck embodying my invention.

Figure 2 is a sectional view of the truck shown in Figure 1, the section being taken approximately in the transverse vertical plane bisecting the truck as indicated by the line 2—2 of Figure 1, with the bolster shown in side elevation.

Figure 3 is a fragmentary sectional view of the truck shown in Figures 1 and 2, approximately in the horizontal vertical plane indicated by the line 3—3 of Figure 2, the left half of the bolster end being shown in top plan view.

Figures 4 and 5 show my novel form of friction shoe, Figure 4 being a plan view thereof, taken from the inner face, and Figure 5 being a vertical sectional view therethrough, approximately bisecting the shoe as indicated by the line 5—5 of Figure 4.

Figure 6 is a fragmentary sectional view comparable to that shown at the right of Figure 1, illustrating a modification of my invention utilizing a plurality of coil springs in each end of the bolster.

Figure 7 is a fragmentary sectional view through the structure shown in Figure 6, the section being taken approximately in the horizontal transverse plane indicated by the line 7—7 of Figure 6.

Figures 8 and 9 illustrate the novel form of friction shoe utilized in the modification illustrated in Figures 6 and 7, Figure 8 being a plan view of the spring-engaging face thereof and Figure 9 a side elevation.

My novel form of truck utilizes a side frame of well known cast steel truss type comprising the compression member 2, the tension member 4, and spaced columns 6 and 8 merging therewith to form the bolster opening 10. The upper portion of said bolster opening, as defined by said compression member, columns and the upper extremities 12, 12 of the central guide portions 14, 14 of respective columns, is relatively wide in order to accommodate therethrough the outboard bolster guide gibs 16, 16 which have a depth

somewhat less than the height of said widened portion of the bolster opening.

Beneath the bolster opening, the tension member 4 may be widened and formed with upstanding outboard and inboard flanges 18 and 20 defining with the top chord of said tension member the spring seat 22 on which may be positioned in usual manner the coil springs, diagrammatically indicated at 24, 24, said springs being illustrated as relatively long travel type. The upper ends of said springs may seat as at 26 against the bottom wall of the bolster 28, guide means therefor being provided on said bolster at 30, 30 and on said side frame as at 32, 32.

The bolster 28 is illustrated in its normal position with the inboard guide lugs 34 of relatively great length bearing against the adjacent columns as at 36 (Figure 3) and the before-mentioned outboard guide lugs of relatively restricted length may have similar position with respect to the opposite or outboard face of each column as at 38. Each side frame column is of general U section, as well seen at 40 in Figure 3, and the inboard face of each column is cored away to permit application of the wear plate 42 against which may seat in flat face frictional engagement as at 44 the friction shoe 46.

Each friction shoe 46 is of the form illustrated in Figures 4 and 5, presenting the flat vertical friction face 48 of rectangular form, said face 48 representing the entire surface of one side of said shoe. The shoe may have lateral side walls 50, 50 with horizontal upper edges 52, 52 affording convenient bearing areas which may seat against the bottom wall of the bolster as at 54 (Figure 1) in case the friction shoe were for any reason forced out of its normal position with respect to the bolster. Between the side walls 50, 50 at opposite sides of each shoe may be formed a diagonal spring seat 56 centrally of which may be provided the upstanding lug or positioning means 58. Each shoe may have therethrough a transverse opening 60 of noncircular section, as clearly seen in the sectional view of Figure 5.

Each shoe may have a diagonally arranged bottom face 62, lateral portions of which may seat as at 64 on the diagonally arranged upper surfaces 66, 66 of the wedgelike lugs 68, 68 formed on the bottom wall 70 of the bolster end at each side thereof, said lugs being aligned transversely and longitudinally of said bolster end. Adjacent the lugs 68, 68 at each side of the bolster may be formed inboard and outboard vertical walls 72 and 74 affording guide means for the friction shoe which may be positioned therebetween, said walls 72 and 74 together with the top and bottom walls of the bolster defining a pocket or opening 75 within which the enclosed friction shoe may have movement laterally of the bolster. The top wall 76 of the bolster may be cored away to form an arcuate guideway or seat 78 for the arcuate compression spring 80, each end of which may seat as at 82 against a friction shoe 46, said spring 80 being hot formed in the arcuate shape illustrated as an additional operation after the spring has been wound, so that the spring assumes a permanent arcuate form, thereby causing a downward component as well as an outward component against the shoes relative to the bolster. The bolster 28 may have the usual vertical reinforcing rib 84 which may be cored away to form an opening 86. (Figure 2) for the spring 80 and said opening may be reinforced by the annular flanges 88, 88 at opposite sides thereof.

The bolster walls 72 and 74, defining the fric-

tion shoe pocket 75, may have aligned openings 90, 90, which have some overlap with the before-mentioned opening 60 in the friction shoe when assembled between said walls so that a bar or other means may be extended therethrough to maintain said shoe in a position within said bolster during application or removal thereof. Also, the outboard web of each column may have a cored opening 92 (Figure 3) affording a seat for 10 a pinch bar or other means which may facilitate moving the bolster laterally when it is desired to fix the position of the shoes within the bolster end. It will be understood by those skilled in the art that the spring and shoes are assembled in the bolster and fixed therein, as above indicated, prior to insertion of the bolster end between the side frame columns as the truck is assembled. Similarly, the shoes are pressed inwardly and secured in a fixed position when it is desired to remove the bolster assembly from the side frame opening. This procedure would be extremely difficult if there were no means of securing the shoes in the bolster assembly.

In the modification illustrated in Figures 6 and 7, I have illustrated my novel arrangement as applied to a bolster end utilizing a plurality of compression springs instead of a single spring. By utilizing a plurality of springs it is possible to secure a somewhat greater arcuation of the spring and more capacity with less stress than is possible when a single spring is used.

In the modification now under consideration, only one column is illustrated and a half section through the bolster, approximately in the vertical plane bisecting the friction shoe. The side frame, generally designated 102, may have the column 104 cut away as comparable to the section of Figure 1 to show the friction wear plate 106 against which the friction shoe 108 may have flat face engagement as at 110. The shoe 108 at each side of the bolster end may be pocketed in the side wall thereof between the inboard and outboard guide lugs 112 and 114 (Figure 7), inboard and outboard lateral walls 116 and 118 forming with the top and bottom bolster walls 120 and 122 a pocket for said shoe. In this modification, the spring engaging face of the shoe may have a plurality of diagonally arranged spring seats 124, 124 with positioning means 126, 126, thereon, said seats being separated by an intervening reinforcing vertical flange 128. Against each spring seat or friction shoe face 124 may be seated a coil spring 130, said springs being diagrammatically illustrated in Figure 7 and each of said springs bearing against a channel or guideway 132 in the top wall of the bolster in manner similar to the previous modification. The longitudinal center wall 134 of the bolster may have a plurality of transverse openings 136, 136 cored therein and flanged therearound as at 138 to afford additional guide means for the springs 130, 130, and prevent their buckling. Within the shoe pocket at each side of the bolster and on the bottom wall 122 thereof may be formed an upstanding lug 139 having a top diagonal face 141 (Figures 6 and 7) against which may seat as at 143 (Figure 6) the arcuate face 145 (Figure 8) on the bottom of the friction shoe. The arcuate face 145 on the bottom of each friction shoe may be convex in both directions in order to permit some tilting of the shoe with respect to the lug 139.

The friction shoe is generally rectangular in plan, as may clearly be seen from the view of Figure 8, having a large flat friction face 140 comparable in size to that of the previous modi-

lication. Transversely through each friction shoe may be cored an opening 142, so positioned with respect to aligned openings 144, 144 in the transverse bolster walls 116 and 118 as to permit the insertion of a rod through said wall openings and the intervening shoe to maintain the shoe in assembled relationship with respect to the bolster and permit assembling or dismantling of the bolster from the side frame opening between the columns, as may be desired for a wheel change or otherwise.

As in the previous modification, the side frame column 104 may have a cored opening 146 (Figure 7) in the outboard flange 148, affording a foot-hold for a fulcrum bar or other means which may be utilized for urging the bolster laterally between the columns when it is desired to insert or remove the securing pin for the friction shoe, such lateral movement of the bolster being effective to compress the arcuate springs between the shoes sufficiently for that purpose.

In my novel arrangement it will thus be seen that I have so arranged the friction shoes and the resilient means compressed therebetween that a substantial vertical component from the resilient means to each shoe urges it downwardly and this vertical component is effective to maintain the diagonal surface at the bottom of each shoe in position against the cooperating sloping surface on the bottom of the bolster. Also, my novel friction shoes are so designed as to afford large bearing area against each column and this condition is conducive to long wear and maximum life. The compression springs are adequately guided against buckling since the arcuate troughs or guides in the top wall of the bolster are supplemented by the openings in the central annular web of the bolster through which the springs extend.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a quick wheel change railway car truck, a truss side frame having spaced columns at opposite sides of a bolster opening, springs in said opening, a bolster supported thereon, said bolster having top and bottom walls, side walls, and transverse walls defining with said top, bottom and side walls aligned friction shoe pockets at opposite sides of said bolster, friction shoes slidably seated on wedge faces in said pockets, and a resilient member compressed between said shoes and bearing against a wall of said bolster, said resilient member having vertical thrust against said last-mentioned bolster wall and bearing against each shoe along a diagonal face to deliver a vertical component thereto.

2. In a quick wheel change railway car truck, a truss side frame having spaced columns at opposite sides of a bolster opening, springs in said opening, a bolster supported thereon, said bolster having top and bottom walls, side walls, and transverse walls defining with said top, bottom and side walls aligned friction shoe pockets at opposite sides of said bolster, friction shoes slidably seated on wedge faces in said pockets, and a resilient member compressed between said shoes and bearing against a wall of said bolster, said resilient member having vertical thrust against said last-mentioned bolster wall and bearing against

each shoe along a diagonal face to urge said shoes against said wedge faces and against respective columns.

3. In a railway car truck, a side frame having spaced columns defining in part a bolster opening, a bolster spring-supported on said side frame between said columns, openings in the side walls of said bolster aligned with said columns, laterally movable friction shoes in said openings, and 10 a resilient means compressed between said shoes and affording a vertical thrust from said shoes to said bolster, said resilient means seating against respective shoes along reversely arranged diagonal surfaces, each of said shoes bearing against the bottom wall of said bolster on spaced diagonally arranged seats.

4. In a quick wheel change railway car truck, a truss side frame having spaced columns at opposite sides of a bolster opening, parallel faces on opposite columns, springs in said opening, a bolster supported thereon, said bolster having top and bottom walls, side walls and transverse walls defining with said top, bottom and side walls aligned friction shoe pockets at opposite sides of said bolster, friction shoes slidably seated on wedge faces in said pockets, and resilient means having opposite ends seated respectively against reversely sloping faces of said shoes and compressed therebetween and bearing against a wall of said bolster to urge said shoes against said respective faces.

5. A bolster assembly comprising a bolster end portion of box section having top and bottom walls, lateral walls, an intermediate web, transverse walls defining with said top, bottom and side walls friction shoe pockets aligned transversely of said bolster, wedge seats at opposite sides of each pocket, friction shoes seated thereon, a single resilient member having its respective 40 ends seated against opposed faces of respective shoes and compressed therebetween and bearing against a wall of said bolster to afford a vertical component between said wall and each of said shoes, and means for retaining said shoes in fixed 45 position in said assembly to facilitate assembling with and dismantling from an associated side frame member.

6. A bolster assembly comprising a bolster end portion of box section having top and bottom walls, lateral walls, an intermediate web, transverse walls defining with said top, bottom and side walls friction shoe pockets aligned transversely of said bolster, wedge seats in said pockets, friction shoes seated thereon, a single resilient member having its opposite ends seated against reversely diagonally arranged opposite faces of respective shoes and compressed therebetween and bearing against a wall of said bolster to afford a vertical component between said wall and each of said shoes, and means for retaining said shoes in fixed position in said pockets to facilitate assembly with an associated side frame member.

7. In a railway car truck, a side frame having spaced columns defining in part a bolster opening, a bolster spring-supported on said side frame between said columns, openings in the side walls of said bolster aligned with said columns, laterally movable friction shoes in said openings, and resilient means compressed between said shoes 60 and affording a vertical thrust from said shoes to said bolster, said resilient means seating against respective shoes along reversely arranged diagonal surfaces.

8. In a railway car truck, a side frame having spaced columns defining in part a bolster open-

ing, a bolster spring-supported on said side frame between said columns, openings in the side walls of said bolster aligned with said columns, laterally movable friction shoes in said openings, and a resilient member compressed between said shoes and affording a vertical thrust from said shoes to said bolster, each of said shoes bearing against the bottom wall of said bolster on spaced diagonally arranged seats.

9. In a railway vehicle, a supporting member having spaced vertical columns, a member spring-supported thereon between said columns with lateral pockets aligned with said columns, friction shoes in said pockets, and arcuate means compressed between the shoes and operative to urge said shoes into engagement with said columns, said arcuate means having respective ends seated against reversely arranged diagonal faces on said shoes to afford a substantial vertical component thereagainst.

10. A box section bolster having top and bottom walls, lateral walls, and an intermediate vertical web, transverse vertical walls merging with said lateral walls to define aligned openings at opposite sides of said bolster, and guide means for an associated spring comprising an arcuate channel in the top wall of said bolster, annular flanges defining an opening in said web, and diagonal friction seats on the bottom wall of said bolster adjacent the transverse walls of each opening.

11. In a railway car truck, a side frame having spaced columns defining in part a bolster opening, a bolster spring-supported on said side frame between said columns, openings in the side walls of said bolster aligned with said columns, laterally movable friction shoes in said openings, and a coil spring of arcuate form compressed between said shoes and having a portion bearing against a wall of said bolster to afford a path for vertical thrusts between said bolster and said shoes.

12. In a railway vehicle, a supporting member having spaced vertical columns, a member spring-supported thereon between said columns with lateral pockets aligned with said columns, friction shoes in said pockets, and a spring member compressed between the shoes and arched against a wall of said supported member and operative to urge said shoes into engagement with said columns, each friction shoe being slidably and rockably seated on a diagonal wall of said supported member.

13. In a railway vehicle, a supporting member having spaced vertical columns, a member spring-supported thereon between said columns with lateral pockets aligned with said columns, friction shoes in said pockets, and an arched metal member compressed between the shoes and operative to urge said shoes into engagement with said columns, each friction shoe being rockably seated on a diagonal surface on said supported member, and said arched member being operative to deliver thrust from a spaced wall of said supported member through said shoes to said diagonal surface.

14. A cast steel bolster having a box section end portion with a top wall, a bottom wall, lateral walls, and a vertical central web, transverse walls defining with said top and bottom walls aligned openings at opposite sides of said bolster with wedge lugs at opposite sides of each opening, and an arcuate guideway in the top wall of said bolster aligned with said openings and extending through said web.

15. In a vehicle, a supporting member having

spaced columns, a member spring-supported between said columns and having friction shoes confined between top and bottom walls thereof for engagement with said columns, said shoes being seated on reversely arranged diagonal portions of said bottom wall, and an arched resilient member compressed between said shoes and having an intermediate portion bearing against said top wall and delivering a substantial vertical thrust therefrom to said bottom wall through said shoes and said diagonal portions.

16. In a railway vehicle, a supporting member having spaced vertical columns, a member spring-supported thereon between said columns with lateral pockets aligned with said columns, friction shoes in said pockets, and arcuate spring means compressed between the shoes and a wall of said supported member and operative to urge said shoes into engagement with a spaced wall of said supported member and also into engagement with said columns.

17. A cast steel bolster having a box section end portion with a top wall, a bottom wall, lateral walls, and a vertical central web, transverse walls defining with said top and bottom walls aligned openings at opposite sides of said bolster with wedge lugs at opposite sides of each opening, and an arcuate guideway in said top wall aligned with said openings.

18. A box section bolster having top and bottom walls, lateral walls, and an intermediate vertical web, transverse vertical walls merging with said lateral walls to define aligned openings at opposite sides of said bolster, and guide means for an associated spring comprising an arcuate channel in the top wall of said bolster aligned transversely of said bolster with said openings, and annular flanges defining an opening in said web.

19. A cast steel bolster having a box-section end portion with a top wall, a bottom wall, lateral walls and a vertical central web, transverse walls defining with said top and bottom walls aligned openings at opposite sides of said bolster with wedge means in each opening, and an arcuate guideway in said top wall aligned with said wedge means.

20. In a railway vehicle, a supporting member having spaced vertical columns, a member spring-supported thereon between said columns with lateral pockets aligned with said columns, friction shoes in said pockets bearing on inclined surfaces of a wall of said supported member at the bottom of said pockets, and an arcuate coil spring compressed between said shoes and bearing against the top wall of said supported member, said spring being operative to urge said shoes against said columns and against said bottom walls.

21. In a railway car truck, a side frame having spaced columns, a bolster spring-supported thereon between said columns with lateral pockets aligned with said columns, friction shoes in said pockets, said shoes having diagonal portions bearing upon diagonal seats on said bolster, and a plurality of coil springs compressed between said shoes and bearing against the top wall of said bolster and operative to urge said shoes against said columns and against said seats.

22. In a railway car truck, a side frame having spaced vertical walls, a bolster and spring-supported on said frame between said walls, pockets at the sides of said bolster end adjacent said walls, friction shoe seats in said pockets, friction shoes on said shoe seats, spaced spring seats on each

friction shoe, and a plurality of arched coil springs compressed between said shoes and bearing against a wall of said bolster and operative to urge said shoes against said side frame walls and to thrust said shoes against said shoe seats.

23. In a railway car truck, a side frame having spaced vertical walls, a bolster end spring-supported on said frame between said walls, pockets at the sides of said bolster end adjacent said walls, surfaces in said pockets affording friction shoe seats, friction shoes having surfaces bearing on said seat surfaces, spaced spring seats on each friction shoe, and a plurality of arched coil springs compressed between said shoes and bearing against a wall of said bolster and operative to urge said shoes against said side frame walls and to thrust said shoes against said seat surfaces, certain of said surfaces having an arcuate form.

24. In a railway car truck, a side frame having spaced vertical walls, a bolster end spring-supported on said frame between said walls, pockets at the sides of said bolster end adjacent said walls, friction shoe seats in said pockets, friction shoes on said shoe seats, spaced spring seats on each friction shoe, and a plurality of arched coil springs compressed between said shoes and bearing against a wall of said bolster and operative to urge said shoes against said side frame walls and to thrust said shoes against said shoe seats, each of said shoes having an arcuate surface bearing against the adjacent shoe seat.

25. In a railway car truck, a side frame having spaced columns, a bolster spring-supported thereon between said columns with lateral pockets thereadjacent, friction shoes seated upon diagonal faces in said pockets and bearing against

respective columns, and resilient means having opposite ends bearing against opposed diagonal faces of respective shoes and compressed therebetween, said resilient means reacting against a wall of said bolster and delivering a vertical component against said shoes.

26. In a railway car truck, a side frame having spaced columns, a bolster spring-supported thereon between said columns with lateral pockets thereadjacent, friction shoes seated upon diagonal faces in said pockets and bearing against respective columns, and resilient means having opposite ends bearing against opposed diagonal faces of respective shoes and compressed therebetween, said resilient means reacting against a wall of said bolster and delivering both vertical and horizontal components of force against said shoes.
